UNITED STATES PATENT OFFICE

HARRISON L. STALEY, OF MARTINSVILLE, INDIANA

BOILER-TUBE CLEANER

Application filed March 2, 1928. Serial No. 258,641.

This invention relates to rotary cleaners which are used for removing scale from boiler tubes and particularly to the type comprising a rotary head and swinging arms connected to the head and carrying rotatable toothed cutters which are thrown out against the scale by centrifugal force.

The effectiveness of this class of cleaners depends on the amount of centrifugal pressure that can be brought to bear upon the rotatable cutters, it being well known to the art that the greater the pressure the faster the cutting action.

Rotary tube cleaners have hitherto been provided with a single row of cutters mounted in a swinging arm, an arrangement that prohibits the successful use of sufficient weight in the arm to produce very high centrifugal pressure for the reason, that when the tube wall is reached and the cutters permitted to run freely over the exposed metal, great damage to both cutters and tube wall results.

It is the object of my invention, first, to provide a cleaner with a plurality of swinging arms, each arm carrying two rows of rotatable cutters so mounted thereon that all the centrifugal pressure is carried at times against the scale on one set of cutters, second, to provide facilities in a tube cleaner whereby the centrifugal pressure of the swinging arm is automatically shifted from one cutting contact to two cutting contacts when the tube wall is reached, and third, to provide a cleaner which eliminates the pounding action caused by the cutters striking projecting pieces of scale, said pounding action being very damaging to both tube wall and cleaner parts.

In the accompanying drawings, Figure 1 is a side elevation of the tool; Figure 2 an end view with head in normal position; Figure 3 is a transverse section on lines A—A in Figure 1 with arms expanded; Figure 4 is a perspective view of the body; Figure 5 is a perspective view of the swinging arm.

The nature of my invention will be best understood by reference to the drawings, it being premised, however, that various modifications of the device may be made without

departing from the spirit and scope of my invention as defined in the appended claims.

Referring to the accompanying drawings, the numeral 2 designates the body of the tube cleaner which is provided with a central hub 55 3 preferably threaded internally to afford connecting means for rotating the same. The body is further provided with a central bar 4 which connects rear head 15 to front head 16, these heads having two pairs of oppositely extending ears 5, 5a with aligning apertures therein for receiving pins 6 to form trunnions for the swinging arms 7. Trunnions 6 can be secured in the ears by riveting or by any other suitable method. I find it 60 65 advisable to remove from the central bar 4 a central part of the diagonal corners 8, 8a to permit cutters 9 on bolts 12 to nest properly when the arm is in closed position.

In the preferred design, the cleaner is 70 equipped with two opposed swinging arms of the U or bifurcated type and as these are identical in construction, I shall describe one only.

The arm is provided with a web or bar 10 75 which is bored longitudinally to afford facilities for pivoting the arm to the body 2 between a pair of the extending ears 5, 5a. Arm members 11, 11a have aligning holes for removably securing two bolts 12, 12a 80 85 therein to act as journals for the toothed cutters, these bolts being mounted in the arm parallel to its axis of rotation. I prefer that the cutter bolts 12, 12a have heads and be screw threaded on one end and extend beyond the front arm member 11a and carry conical shaped cutters 13 between the bolt head and said arm member. The holes in the rear arm member 11 are threaded to receive the threaded end of the cutter bolts. 90 To bring the conical cutters 13 beyond a point of interference with the front head 16 when the arm is in closed position, hub extensions 14 are provided on the arm member 11a. The arm is held within certain 95 swinging limits by stops 17 which engage the side of the bar 4 on its outward movement.

I have devised means whereby cutters on the bolt 12 can be combined with the weight 100

of the swinging arm 7 to greatly increase the centrifugal pressure on the cutters 9 mounted on the bolts 12a until the tube wall is reached when a division of this pressure occurs, part of it being then carried by cutters on the bolt 12.

I have further discovered that because of the very great pressure or force exerted on the cutters mounted on the bolt 12a by the cleaner being driven at high rotation, no sharp rebounding action occurs when it strikes a projecting piece of scale, and that the cleaner is held firmly against the work.

I have lastly discovered that in any modification of a cleaner which carries out this principle, the axis of the cutter mounted on the bolt 12a will always be to one side of a straight line drawn from the pivot 6 to the axis of the cutter on the bolt 12 and that when all these points are connected by lines, they make an obtuse triangle.

It is to be understood that tube cleaners of this type must be arranged in size for one particular diameter of boiler tube.

Although arrangement of relations can be worked out whereby cutters of the same diameter can be mounted on the bolts 12, 12a, I prefer to use cutters of different diameters and place the cutters of larger diameter on the bolt 12a which is located in the arm nearest the pivot 6.

No claim for novelty is made for cutters which are of the radial tooth variety well known to the art.

Having fully described my invention, I claim as new:

1. A tube cleaner comprising a body adapted to be rotated, arms pivoted thereto to swing transversely to the axis of rotation, two rows of cutters mounted rotatively on each of said arms, the axis of one row of cutters describing a larger arc than the axis of the other row.

2. In a tube cleaner, a rotary body having front and rear heads, swinging arms pivoted to the head members, cutters of different diameters mounted on each of said arms with the cutters of larger diameter nearest the pivot points of said arms.

3. The combination of a body having lateral projections thereto, U shaped arms pivoted to the projections, a plurality of bolts or pins secured to each of the arms parallel to the axis of rotation, cutters of different diameter mounted on the bolts, the cutters of larger diameter being mounted on the bolts nearest the pivot points of said arms.

4. In a tube cleaning device, the combination of a body having a flat central section, front and rear heads integral with the central section, means for driving the device attached to the rear head, bifurcated arms pivoted between the front and rear heads, two rows of cutters of different diameters carried by each of the arms, the cutters of

larger diameter being mounted nearest the pivot points of said arms.

5. The combination of a body having oppositely disposed lateral projections thereon, swinging arms pivoted to the projections, two rows of cutters mounted rotatively on each of the arms in such a manner that lines connecting the axes of the cutters with each other and with the axis of the arm make an obtuse triangle, the apex of whose obtuse angle is in the direction of the outward movement of said arm.

6. The combination of a tube cleaning device having a body adapted to be rotated, swinging arms each having plural rows of rotatable cutters mounted thereon and being pivotally secured to the body, and stops on the swinging arms to limit the outward movement thereof substantially as described.

7. A tube cleaner comprising a body adapted to be rotated, a plurality of arms pivoted thereto to swing transversely to the axis of rotation, plural rows of cutters mounted rotatively in each of said arms in such relation that the axes of no two rows of cutters are equal in distance from the axis of the pivot point of said arm.
